TABULATING MACHINE

William W. Lasker, Brooklyn, N. Y., assignor to
Remington Rand Inc., New York, N. Y., a corporation of Delaware

Application July 27, 1931, Serial No. 553,317

10 Claims. (Cl. 235—58)

This invention relates to tabulator machines and more particularly to the means for printing alphabetical characters from the so-called "spelling field" of a card.

5 It has been common practice to equip tabulators, as for example the Powers, with alphabetic sectors for translating the perforations of a card's spelling field. Such alphabet sectors of necessity contain more than twice as many type 10 characters as do the usual numeric sectors. Heretofore the adjustment of such sectors to align the selected type at the printing line has required a correspondingly greater time, hence tabulator machines equipped with alphabet sectors have 15 had to be operated at speeds materially slower than that of corresponding machines without such equipment. In the well known Powers machines, the perforated cards are first stacked in a magazine from which they are ejected seriatim 20 to a sensing box, in which the cards are temporarily held during translation, a condition corresponding to such translation being then set up in a stop basket preparatory to actuating the type sectors to the printing position. After this, the 25 sensed or translated card is fed to a receiving magazine and another card is fed forward to be translated for another line of printing.

One object of this invention is to provide means whereby tabulator machines, provided with alphabetic type sectors, may be run at a much higher speed than has heretofore been deemed practical.

Another object of this invention is to provide a simplified mechanism for retracting the alphabet printing hammers a short distance, immediately after they have struck the type, so that the type sectors may begin their return stroke immediately after printing.

Another object of this invention is to move a universal alphabet sector restoring ball with substantially a simple harmonic motion, so that the said sectors may be restored by it with substantially the same type of motion.

Another object of this invention is to restore the printing hammers at the time that the speed 45 of the universal ball is a minimum.

Another object of this invention is to speed up the printing hammers by reducing the distance through which the said printing hammers travel to strike a printing blow.

50 Another object of this invention is to restrain the alphabetical printing hammers during totaling operations.

To the above and other ends the invention comprises certain new features of construction and 55 certain new combinations and arrangements of

parts which will be fully set forth hereinafter and particularly pointed out in the claims.

In the accompanying drawings,

Fig. 1 is a front to rear diagrammatic elevation showing a Powers tabulator in which the invention is embodied.

Fig. 2 is an approximate full sized elevation of an alphabet printing sector in initial position.

Fig. 3 is a detail view showing the position of a hammer at the end of its percussive stroke.

Fig. 4 is a view corresponding to Fig. 3 after the hammer has had its momentum spent.

Fig. 5 is a cross sectional elevation showing the mechanism for operating the alphabet sector universal bar.

Fig. 6 is a rear view of the alphabet unit.

Fig. 7 is a diagrammatic view showing the mechanism for restraining the alphabetic hammers during the space and total strokes of a totaling cycle.

Fig. 8 is a face view of the type on a type carrier.

In the drawings, the invention is shown applied to that form of Powers tabulating machine disclosed in the patent to William W. Lasker, No. 2,044,119, dated June 16, 1936. In this patent the "card hopper 11" corresponds to magazine 11 hereof, "arm 21" to arm 13, "feed rolls 87 and 88" to feed rolls 14, "card stop 236" to card stop 16, "main shaft 25" to main shaft 20, "eccentric 183" to eccentric 19, "sensing pins 174" to sensing pins 21, and "pins 158" to pins 24, "slide 161" to slide 28, "slide 321" to slide 138, "shaft 342" to shaft 139, "interponent 330" to interponent 1380, "bail 338" to 1381, and "shaft 336" to shaft 1382. (See Figs. 1, 10, 19 and 27 of the patent.)

A stack of pre-grouped perforated cards 10 is first inserted into the magazine 11. During the regular operation of the machine, the cards are ejected seriatim from said magazine and individually tabulated. The cards are extracted from the stack by means of the usual picker knife 12 operatively connected to an arm 13 of the usual picker mechanism the cards being then engaged successively by pairs of feed rolls 14 and 15 arranged to move the card rearwardly against an effectively positioned card stop 16 which holds the card stationary between the pin boxes which are indicated in general by the reference numerals 17 and 18 (Fig. 1). While the card is held in the sensing position, the lower, or sensing pin, box 18 is moved upwardly by a mechanism including a link embracing an eccentric disk 19 secured to the main shaft 20. The said main shaft is continuously rotated by a usual form of prime mover such as an electric motor, (not

shown). The shaft 20 makes one rotation for each card tabulated and such rotation of this shaft is designated a cycle.

The lower pin box 18 is provided with a plurality of rows of sensing pins 21 corresponding to all of the possible perforations in the cards. If there is no hole in the card being tabulated or sensed, the pins 21 are held back when they strike the card 9 as is shown in the case of the 5 single pin 21 illustrated in Fig. 1. If, however, there is a hole coinciding with any one or more of the sensing pins 21, then that pin, or pins, is not arrested by the card and due to the movement of the pin box 18, said pins will pass through 10 the perforations in the card. Just before the pins, which pass through perforations in the card, strike the associated upper, or reading retaining, pins 24, they will be locked stationary relatively to the pin box 18 by the series of locking slides 22 15 operatively connected with a cam-controlled universal locking slide controlling bail 23 which travels with the pin box 18. The universal locking bail 23 is controlled by a stationary cam 27 which is timed so that the above described locking 20 takes place at the time stated. Further upward movement of the pin box 18 results in positively elevating the corresponding wires 25, situated in a structurally well known translating device 26 to 25 set the corresponding stops 65 for determining the extent of movement of the type carrying 30 sectors 35.

At about the time that pin box 18 has reached its highest position, the upper pins 24 are locked in their raised positions by means of the spring 35 pressed locking slides 28 which cooperate with locking studs on said members 24. Due to the continuous rotation of the eccentric 19, the said members 24 will remain in their adjusted elevated positions while the pin box 18 is receding downwardly. When said pin box 18 has reached substantially that position where the pins are fully retracted from the perforated card, the stationary cam 27 operates the universal bail 23 to release the locked sensing pins 21.

45 Just after the perforated card has been freed from the pins 21, the card stop 16 is elevated and the now sensed card is fed onward by the pairs of skid rolls 15 to the ejecting rolls 29, and thence to the storage magazine 30.

50 The mechanism for printing alphabetic characters includes a number of pairs of arms which are journaled on the frame supported shaft 37 and are normally held in the relative positions shown in Fig. 2 by spring pressed catches 81. The 55 arm 35 carries a plurality of usual spring restored plunger types 36; and is connected to arm 83 by means of a pin 84 fixed to arm 35 and a spring urged catch 81 pivoted on member 83. Pin 84 and catch 81 are adapted to engage each other. 60 The members 35 and 83 tend to rotate relatively to each other because of the tensioned spring 86 connecting them, which spring also urges the latch 81 to the position shown in Fig. 2 through the bell crank lever 88 pivoted on a stud 89 rigid 65 with member 83 as shown in U. S. Patent to Lasker, No. 1,768,526, granted June 24, 1930. The member 35 is provided with an upwardly and rearwardly extending arm which is shaped to provide two hooks, one indicated at 61 for spring 60 70 and the other indicated at 87 for spring 86.

75 The tension of spring 60 which extends from hook 61 on the rearwardly extending arm of type sector 35 to a spring anchor on bar 57 will cause the type sector 35 to move forwardly and upwardly when the universal bail 39 is advanced

during the operation of the machine. Stops 65 control the positioning of stop sector 83. It has been described above that the differential stops 65 are positioned by a reciprocation of the sensing box 18 while a perforated card is being read. Each of the stops 65 is provided with a stud 71 which lies forward of the associated cam face 72 of slide 66 which is under the tension of spring 73 through the medium of bell crank 70. Said slide 66 is mounted so as to have a sliding 10 transverse movement on frame supported rods 67, 68. The forward end of the bell crank lever 70 has pivoted thereto the zero stop 64; hence, when any differential stop 65 is elevated, its stud 71, by cooperating with a cam face 72, shifts the 15 bar 66 rearwardly to rock bell crank 70 and withdraw the zero stop 64. When any of the first eleven characters of the alphabet are sensed, one of the eleven stops 65 is elevated to determine the proper position of the type. If the twelfth character is sensed, disconnector 80 is elevated. The elevation of this element rocks catch 81 counter-clockwise, causing the release of pin 84. The tension on spring 86 then causes arm 35 to advance the full extent allowed by slot 85 in member 83. 20 When any of the last eleven characters are sensed a stop 65 and disconnector 80 are both elevated, pin 84 is released permitting type carrier 35 to be extended and arm 83 is advanced to the position indicated by the elevated stop 65. There 25 are, therefore, twenty-three possible type positions which number is one more than double the number of stop positions permitted by the stop basket elements.

Referring to Figs. 2 and 6, it will be seen that 35 the universal bar 39 is carried at the lower ends of a pair of frames 40 pivoted on the supporting shaft 37. Said arms are pivotally connected through pins 45 fixed thereon to the links 44 extending rearwardly to pins 43 of the cranks 41. 40 Each of the cranks 41 (Fig. 5) is fixed by some suitable means such as the rivets 47 to a long hubbed gear 46. Each of the hubs of said gears is pinned to the shaft 42 so that the crank, gear and shaft rotate as a unit. Each of the gears 45 46 meshes with a companion gear 54 pinned to the auxiliary main, sometimes called rotation, shaft 50.

A complete rotation of the shaft 50 correspondingly causes a complete rotation of the cranks 41 50 thus shifting the universal bail 39 forwardly and upwardly, as shown in Fig. 7, and then returning to the position shown in Fig. 2, and during such movement the types 36 are positioned to the printing line of the platen 95 under the control 55 of previously set stops 65 or under the combined control of the disconnector 80 and stops 65.

Shaft 50 is a rotation shaft which is connected through a pair of beveled gears 52 (Fig. 1) to the frame supported downwardly extending connecting shaft 53, the lower end of which terminates in one of a pair of similar beveled gears 51, one of which is fast to the main shaft 20. The main shaft 20 rotates in the direction of the arrow shown in Fig. 1 and gears 52 are so located that 60 shaft 50 rotates in the opposite direction but with the same speed of rotation.

For effecting printing by the positioned type, spring pressed hammers which are journaled on a frame supported shaft 118 are provided. The 70 printing hammers 97 are normally restrained in cocked position by the spring pressed latches 104 each engaging a tooth at the lower end of each of said hammers, as shown in Fig. 2. Each of the latches 104 has pivoted near the midpoints 75

thereof, a spring pressed interponent 103 which lies above the forwardly extending arm of its companion bell crank lever 98 which bell crank is loosely pivoted on the printing element frame supported shaft 99. When a type carrier element 35 moves from its normal position shown in Fig. 2, to that determined by any stop 65, the cam surface 101 contacts with the rearwardly extending arm of the bell crank member 98 to rock said member downwardly thus elevating the interponent 103 slightly. When the selected type 36 has been positioned at the printing line, (see Fig. 7) universal bar 39 has reached the position shown, also, the universal hammer releasing bail 119 has been rocked to substantially the position shown and in such position it has shifted all the elevated interponents 103 forwardly to release the latches 104 and permit the springs 109 to urge the corresponding printing hammers 97 to strike a percussive blow against the then positioned type 36.

The bail 119 (Figs. 2, 3, 4 and 7) is carried by a pair of arms fixed to the shaft 118. Also fixed to said shaft 118 is an arm 120 to which is pivoted a link 121 extending downwardly to a pivot 125 on cam 122 of the type usually used for engaging and disengaging totalizers which cam is fixed to the main oscillatory shaft 123. A pitman 128 is pivoted to the upper end of arm 129 (Fig. 1), which arm is fixed to shaft 123. Said pitman extends rearwardly to pin 127 which extends laterally from crank 126 fixed to the rotation shaft 50. When the type carriers have returned to normal, the cam 101 does not contact with the arm 98 so that the spring 107 attached to the interponent 103 lowers the rear end out of the path of the hammer releasing bail 119 so that a printing hammer 97 will be restrained unless the associated type carrier is moved from normal or zero position. Each of the members 83, when it reaches normal position abuts against a fixed portion of the frame work to limit further reverse movement. When a member 83 is stopped during the return stroke of the universal bail 39, the member 35 is forced rearwardly, independent of member 83, and such independent motion continues until crank pin 43 has reached its upper dead center position. At about the time this point is reached, the spring pressed latch 81 engages the pin 84 thus again connecting members 35 and 83.

In Figs. 1 and 2 the mechanism is shown in its initial position. In returning to this position from that shown in Fig. 7, sector 35 is first picked up by universal restoring bar 39 and moved rearwardly, spring 86 causing 83 to move with it until 83 is arrested, as is usual in mechanism of this sort, by any suitable means. Bar 39 then carries 35 a short distance beyond its normal position so as to enable latch 81 to engage pin 84. This latching occurs at the dead center of pin 43. In this position sector 83 is in its rearmost position against an abutment (not shown) on the framework of the machine. Crank 41 then moves far enough beyond dead center to allow bar 39 to advance a distance sufficient to allow sector 83 to contact zero stop 64. If interponent 80 is operated to release latch 81 before bail 39 has advanced to allow positioning of the type sectors, 70 sector 83 is displaced with respect to 35 a distance such that the two sectors will not again be engaged by latch 81 until after bail 39 has completed its cycle.

Each of the printing hammers 97 is provided 75 with a forwardly extending finger 117 which lies

in the path of the rearwardly extending end of its associated spring pressed buffer arm 112. Just before the hammer 97 reaches the positioned type, as shown in Fig. 4 the associated finger 117 will contact the associated arm 112. Each of the buffers 112 is loosely fastened on a printing unit supported shaft 113 and is held in its normal position shown in Figs. 2 and 4 by a spring 115 which is strong as compared to the relaxed strength of the printing hammer actuating springs 109. The printing hammers are released when the pins 43 of the cranks 41 have reached their approximate lower dead center position, as shown in Fig. 7. A portion of the momentum of the released printing hammers 97 is absorbed by partially stretching the springs 115, the remainder being used for effecting a percussive printing blow (see Fig. 3). The partially stretched springs 115 then slightly withdraw the hammers 97 to the position shown in Fig. 4 thus permitting the carriers 35 to begin their return excursions before the printing hammers are cocked. The hammers are not retracted by the bail 119 until the pin 43 has passed very considerably beyond its lower dead center position. Therefore, the partial hammer retraction by buffers 115 permits a more rapid operation of the alphabet sectors.

During a total printing operation, the machine goes through an idle cycle which is used for restoring tripped transfers (if any), then through a total taking cycle. It is desirable to restrain the alphabet printing hammers during such cycles, since the alphabetic sectors might occasionally be released during the change-of-designation sensing operation, which would cause undesired printing by these sectors. Referring to Fig. 1, it will be noted that a slide 138 is associated with each order of the reading retaining pins 24. This slide 138 is spring pressed rearwardly by a device such as that shown in Fig. 19 of the cited Patent No. 2,044,119.

Slides 138 may be pre-selected by positioning a manually settable interponent 1380 between said slides and a universal bail, thereby controlling the functions of total control shaft 139 through 45 a pawl and ratchet mechanism which is actuated by a cam (such as 360, Fig. 27 of the cited Patent No. 2,044,119) on main shaft 20.

When there is a change in the subject matter of the record, slides 138 are moved forwardly by 50 the movement of any upper, or reading retaining, pin 24. This motion of slides 138 causes the forward end thereof to contact interponent 1380 which has been set in the process of preselecting the column in which the change-of-designation is 55 to be made effective. The motion of 138 will move interponent 1380 and bail 1381 causing an oscillation of shaft 1382 which shaft corresponds to shaft 336 (Fig. 10) of the cited Patent No. 2,044,119. This motion of shaft 1382 will trip 60 the latch (not shown, but the same in shape and identical in function to latch 352, Fig. 19 of the cited patent) of the automatic totaling device to release an arm such as 346 so that the next turn of shaft 20 will cause the cam, such as 360, to 65 raise a rod, such as 354. The raising of this rod will actuate the released arm to force a pawl such as 344, which is mounted thereon, against a ratchet, such as 343, thus turning the ratchet and causing the shaft 139 to be turned, thereby actuating the mechanism for the control of non-print bail 135. A cam 155 is mounted upon shaft 139, which shaft controls the function of total shaft 1561. The mechanism for this control consists of lever 157, link 156 and arm 1560. When 70 75

shaft 139 is turned, lever 157 is rocked counter-clockwise, pulling link 156 downwardly and rocking arm 1560 and shaft 1561 clockwise to actuate the mechanism associated with totaling. Since 5 the control of instrumentalities for the taking of totals by a shaft such as 1561 is a well known expedient, having been in use in the so-called Powers tabulators since August 1915 and adequately disclosed in patents to Penney No. 10 1,317,454 (shaft 40), Lasker No. 1,376,555 (shaft 19), Penney and Davidson No. 1,376,572 (shaft 243), and Lasker No. 1,388,271 (shaft 32), a detailed description will not be given herein.

The mechanism associated with the control of 15 non-print bail 135 as shown in Figs. 1 and 7 and consists of cam 140 which is mounted on shaft 139, spring urged bell crank 141 which is journaled on shaft 143, link 144, lever 145, shaft 146 and link 148. When shaft 139 and cam 140 are 20 actuated spring urged bell crank 141 is rocked clockwise elevating 144 and rocking lever 145. This motion pulls 148 downwardly and swings non-print bail 135 counterclockwise to a position such that the lip on the lower edge of the bail is 25 interposed in the path of the hook at the lower forward end of hammer 97.

When cam 140 is turned to permit the follower on bell crank 141 to rest in one of the notches of said cam the above described mechanism will 30 move the non-print bail 135 out of the path of print hammer 97, and when in the operation of machine latch 104 releases print hammer 97, printing of the character set on the type carrier 35 is permitted.

35 What I claim as new and desire to secure by Letters Patent is:

1. In a machine of the class described, a series of type carriers, means for setting said type carriers to differential positions, said means including record sensing means, means for effecting printing from the positioned type carriers and means comprising an intermittently operable cam shaft, the operation of which is initiated by the ascent or descent of said type carrier setting means for restraining said means for effecting printing.

2. In a machine of the class described, a series of type carriers, means for controlling the positioning of said type carriers to differential positions said means including record sensing means, means for effecting printing from the positioned type carriers, means associated with said sensing means for initiating a change in the operation of the machine, and means under control of the 55 change initiating means for restraining said printing means.

3. In a machine of the class described, the combination of a card sensing mechanism, a series of type carriers, means under control of said 60 sensing mechanism for determining the extents of movement of said type carriers, automatic means for sensing the end of a group of pre-selected cards, a cam, means controlled by said last mentioned sensing means to cause the actuation of said cam, and means associated therewith to render said printing mechanism ineffective.

4. In a machine of the class described, a perforated record card; a type carrier and hammer mechanism associated therewith, means for controlling the extents of movement of the said type carrier said means including record sensing 5 mechanism and reading retaining mechanism, and means controlled by said reading retaining mechanism for rendering said hammer mechanism ineffective.

5. In a machine of the class described, a printing mechanism including type carriers and hammer mechanism associated therewith, record controlled means for governing the extent of actuation of the type carriers for positioning type to be struck by said hammer mechanism, and record 15 controlled mechanism for restraining said hammer mechanism, said restraining mechanism including a normally ineffective hammer blocking bail.

6. In a machine of the class described, the combination of a perforated record card, records, record sensing means, a series of extensible type carriers, a corresponding series of normally locked hammers for striking type carried by said carriers, means under control of each of the carriers for releasing the lock of its hammer, and universal means controlled by said record card for rendering said releasing means ineffective.

7. In a machine of the class described, the combination of perforated record cards, record sensing means, a series of extensible type carriers and a corresponding series of normally locked hammers for striking type carried by said type carriers, means for causing the release of said normally locked hammers, and means under control of said record card perforations for blocking said hammers against actuation.

8. In a machine of the class described, the combination of record sensing means, totaling means, extensible type carriers and resilient hammers associated therewith, means, the action of which is initiated by said sensing means and which is actuated by said totaling means for restraining the action of said hammers, and means which move according to the principle of simple harmonic motion for restoring said type carriers.

9. In a machine of the class described, a series of type bars; means, including record sensing pins and movable reading retaining pins for controlling the differential positioning of said type bars; means for effecting printing from the positioned type bars; and means operable by the action of any of said movable reading retaining pins for causing said printing means 50 to be restrained.

10. In a machine of the class described, the combination of a card sensing mechanism, a series of movable type bars, means under control of said sensing mechanism for positioning said type bar for printing, printing hammers, means responsive to the action of said sensing means for initiating a change in the operation of the machine, and means associated with said last named means for restraining said printing hammers.

WILLIAM W. LASKER.
